[57] CLAIM

The ornamental design for a loudspeaker, as shown and described.

DESCRIPTION

FIG. 1 is a top, front and left side isometric view of a loudspeaker showing my new design;

FIG. 2 is a top plan view thereof;

FIG. 3 is a left side elevational view thereof;

FIG. 4 is a right side elevational view thereof;

FIG. 5 is a top, front and left side isometric view of a second embodiment of the loudspeaker illustrated in FIG. 1;

FIG. 6 is a top plan view of the embodiment disclosed in FIG. 5;

FIG. 7 is a left side elevational view of the embodiment disclosed in FIG. 5;

FIG. 8 is a right side elevational view of the embodiment disclosed in FIG. 5;

FIG. 9 is a top, front and left side isometric view of a third embodiment of the loudspeaker illustrated in FIG. 1;

FIG. 10 is a top plan view of the embodiment disclosed in FIG. 9;

FIG. 11 is a left side elevational view of the embodiment disclosed in FIG. 9; and

FIG. 12 is a right side elevational view of the embodiment disclosed in FIG. 9.

The rear and bottom of the loudspeaker of the three embodiments are plane and unornamented.
